UNITED STATES PATENT OFFICE.

JOHN H. PENDLETON, OF BROOKLYN, ASSIGNOR, BY DIRECT AND MESNE ASSIGNMENTS, TO THE RAPID TRANSIT CABLE COMPANY, OF NEW YORK, N. Y.

CABLE RAILWAY.

SPECIFICATION forming part of Letters Patent No. 387,994, dated August 14, 1883.

Application filed January 25, 1887. Renewed June 13, 1888. Serial No. 276,934. (No model.)

To all whom it may concern:

Be it known that I, JOHN H. PENDLETON, of Brooklyn, in the county of Kings and State of New York, have invented an Improvement 5 in Cable Railways, of which the following is a specification.

Difficulty has heretofore been experienced in cable railways where one track crosses another in preventing the cables rubbing against 10 each other and in maintaining a hold or grip upon one of the cables while the car is crossing the intersection.

I elevate the tracks at the intersection by 15 gradually-inclined approaches, so that one cable can be passed entirely below the rails of the crossing track without being depressed materially, or without the cross-ties being cut off, and the other cable is carried along in 20 the usual level and guided by peculiar rollers, so as to be raised or lowered through narrow openings between the rails of the crossing track.

In the drawings, Figure 1 is a plan of the 25 intersecting tracks and of the cables and rollers. Fig. 2 is a vertical section at the line *x x*, and Fig. 3 is a similar section at the line *y y*.

The tracks A A and B B are upon the 30 respective ranges of cross-ties A' B', and these are either set in the earth or supported upon 35 girders D D', such as used in elevated-railway structures.

The intersecting frogs E, that form the rails and intervening grooves, are of any ordinary 35 character; but at 3 3 there are complete separations in the crossing rails, forming openings that are wide enough for the cable F to be lifted up or allowed to descend, and this cable

F runs upon the sheaves or guide-wheels H 40 H, having horizontal axes, and made in any usual or desired manner, and this cable F in its normal condition is nearly a straight line as it passes along over the wheels H H.

The guide-rollers I I are in pairs at the 45 outsides of and adjacent to the openings 3 in the rails, and such guide-rollers are upon vertical axles in suitable bearings below the

rollers, and each roller is largest in the middle and is rounded upon its periphery, and it is placed with its center portion at or near the 50 level of the rail, so as to guide the cable and prevent it cutting upon the ends of the rails at the openings 3, when said cable is lifted up or allowed to drop; hence the car traveling upon the track A can retain the hold upon 55 the cable by the grip in passing the intersection.

In order to depress the cable K of the track B sufficiently to cause it to travel freely beneath the cable F, I use the grooved wheels 60 or sheaves L, beneath which such cable K travels. These grooved wheels are adjacent to the track A, and the amount of the depression is necessarily such that the cross-ties of the track B would have to be cut off 65 were it not for the fact that both tracks, A and B, are inclined upwardly to the frogs, as shown, so that the necessary space is obtained, and the cable K passes through holes in the sill-pieces A' of the tracks A, that are 70 introduced at the intersections below the frogs. The blocks P upon the cross-ties are used for raising the inclined rails. It will now be understood that the grip that connects the cable K to the car upon the track B has 75 to be opened and the cable dropped while the car is passing the crossing, and that the cable is picked up and gripped after the car has passed such crossing; but with cars upon the track A the cable does not have to be 80 dropped. This improvement allows for the use of cables especially at the intersections of elevated-railway structures without making any changes in the iron portions of the structure. 85

I claim as my invention—

1. The combination, with the intersecting tracks and the respective cables, of frog-plates or rails that are separated at 3, for allowing the cable F to be raised through such separation or opening, and pairs of guide-rollers 90 to guide the cable and prevent contact with the frog-plates or rails, substantially as set forth.

2. The combination, with the intersecting tracks and frog-plates or rails having openings at 3, of the guide-rollers I in pairs, the supporting-wheels, the cables F and K, the 5 rollers L, for holding down the cable K at the crossing, and the blocks for supporting the inclined rails of the track, the intersection being elevated, substantially as set forth.

Signed by me this 16th day of December,
A. D. 1886.

J. H. PENDLETON.
